UNITED STATES PATENT OFFICE

HERBERT EDWARD PAGE, OF SYRACUSE, NEW YORK, ASSIGNOR TO UNITED STATES
HOFFMAN MACHINERY CORPORATION, OF NEW YORK, N. Y., A CORPORATION OF
DELAWARE

AUTOMATIC BOILER WATER FEEDER

Application filed August 4, 1926. Serial No. 127,121.

This invention pertains to automatic water feeders for use in connection with steam boilers. More specifically, the invention is designed for utilization in connection with boilers employed for the purpose of supplying steam to garment pressing machines and the like.

The main object of the invention is to provide a structure by which water may be fed to a steam boiler in which steam is present under greater or less pressure and this without any work imposed upon the attendant, such as pumping, it being necessary only for the attendant to manipulate certain valves.

15 An embodiment of the invention is shown in the annexed drawings wherein

Figure 1 is a perspective view of a steam boiler surmounted by a water feeding tank and interconnected with the boiler in such 20 manner that the water may pass from the tank automatically to the boiler upon the manipulation of certain valves, and

Figure 2 a detail sectional view illustrating means located in the steam relief pipe to constrict the steam outflow for purposes which will hereinafter appear.

In the drawings, 1 denotes the boiler which may be of any approved type and heated in any suitable manner, as by a gas burner. Located directly above the boiler is a feed water tank 2 supported in any suitable manner as by a casting 3, it being understood however, that this particular arrangement is not essential to the operation of the invention.

35 The boiler is provided with the usual gage glass 4 and a similar gage glass 5 is provided for the tank 2. 6 indicates a line adapted to be connected to a suitable water supply line, in which the water is under pressure. A 40 check-valve 7 to prevent reflow is located in the line as is also a valve 8. Said line, through a lateral connection 9, is connected directly into the bottom of the feed water tank while a second lateral line 10 extends downwardly 45 and is provided with a hand control valve 11. At its lower end the pipe 10 is provided with a lateral branch 12 in which is located a check-valve 13, the lateral 12 being connected into a suitable pipe 14, which in turn is connected to 50 the bottom of the boiler. A lateral 15 extends

from the lateral 12 and leads through a valve 16 and a check-valve 17 to the bottom of a hand pump 18. The pump is also connected into the lower portion of a bucket 19, as at 20, in order that water may be removed from the bucket by the pump and forced into the boiler. The bucket is designed to catch any water which may pass downwardly through a pipe when the water tank is being vented as will hereinafter appear. The pump is provided 55 with an overflow lip which extends over the bucket to catch any leakage that may pass around the piston or through the packing of the pump.

A suitable draw-off valve 21 is connected 60 to the branch 14 in order that the boiler may be drained or purged when desired.

A pipe 22 is connected into the upper end of the tank and extends downwardly therefrom to a T or fitting 23. From the lower end of the T there extends a pipe 24, the pipe being provided with a hand operated valve 25 and terminating in a pet or tri-cock 26 which is connected into the water space of the boiler. Pet-cocks 27 and 27^a are also connected into 75 the boiler.

Extending from the T 23 is a branch pipe 28 provided with a hand valve 29, the pipe 28 extending downwardly and being carried over so that its end overlies the bucket.

80 Located in the down-going leg of the pipe 28 there is provided a fitting best shown in Figure 2. Mounted in the lower end of a nipple 30, forming a part of the line 28, is a Venturi nozzle 31, which nozzle serves to restrict the steam flow downwardly through the pipe 28 to such an extent that steam cannot pass from the lower end of the pipe 28 except under reduced pressure. In other words, the venturi allows the steam to expand in the lower portion of the pipe after it passes out of the Venturi nozzle and, as a consequence, steam cannot pass from the lower end of the pipe 28 with such force as to blow the water out of the bucket in case there is 85 any water in the bucket.

90 The tri-cock 27, above referred to, may be utilized in the ordinary way although its presence is not essential.

95 A safety valve 32 of any approved type is 100

shown as connected into the upper portion of the boiler as is also a steam pressure gauge 33.

Operation

In order to fill the tank 2 we may consider that the globe valves 25, 11, 29 and 8 are closed, it being understood that the valves 16 and 21 are never open except on special occasions. Under these conditions the water feeder 2 is entirely disconnected from either the boiler or the water feeder supply line 6. Starting from this point, if the valve 29 is opened it will relieve any steam pressure which may exist in the tank 2 by allowing the steam to flow down through pipe 28 and into the bucket 19. Opening valve 8 at the same time, or immediately thereafter, will allow water to flow through the check-valve 7 and valve 8 up through pipe 9 into tank 2. The water must follow this course since it cannot go down through the valve 11 since this valve is in a closed position. Under these conditions it requires very little water pressure to force water into the tank due to the fact that the valve 29 being open allows the pressure in the tank to become practically atmospheric. After the tank has been filled with water, which can be seen by the gauge glass 5, valves 8 and 29 are closed in order to place the automatic water feeder in full operation. It is then necessary to open valves 11 and 25 which permits steam to flow from the boiler through the tri-cock connection 26 and pipe 24—22 into tank 2 and allows the water to flow from said tank through the pipe 10—12—14 and past the check-valve 13 into the bottom of the boiler.

In order that steam may flow from the tri-cock connection 26 and through pipe 24 the water supply in the boiler must be below the tri-cock connection 26. Consequently, as the water flows into the boiler from the feeder tank, the water level in the boiler rises until finally it reaches the tri-cock connection 26 at which point the water fills the opening and allows no more steam to flow upwardly through the pipe 24. This almost immediately causes the steam pressure in the tank 2 to drop and prevents a further flow of water through the pipe 9—10—12—14 and check-valve 13 to the bottom of the boiler.

During the process of boiler operation, as the steam is used from the boiler and the water level is consequently lowered unsealing the boiler connection to the tri-cock 26, steam is again allowed to flow up into the tank 2, as above described, which permits more water to be fed into the bottom of the boiler, as above outlined.

This cycle of procedure is automatic until finally the water in the water feeder tank is exhausted at which time it again becomes necessary to close the valves 25 and 11 and open valves 8 and 29 refilling the tank as above described.

It will be noted that the check-valve 7 prevents steam flowing into the water line 6 in case the initial steam pressure of the tank should be greater than the water pressure in the line when the valve 8 is first opened and before the valve 29 has had time to relieve the steam pressure. It is likewise to be noted that the check-valve 13 prevents any great surge of water from the boiler to flow up into the feeder tank. When the tank is in the operating position with the valves 29 and 8 closed and 11 and 25 open it also prevents this occurring if the valve 25 should be left in closed position and valve 11 open, as this would then allow the water to be forced out of the boiler and through the bottom of the water feeder tank were it not for the protective action of the check-valve 13.

When the valve 29 is opened in the due course of operation, in order to relieve the steam pressure in the tank 2, if nothing were done to constrict the steam flow, the operator might inadvertently open said valve to such an extent as to pass steam through the line 28 and into the bucket 19 with sufficient force to blow any water which the bucket might contain outwardly therefrom and over anything adjacent to the boiler. The device shown in Figure 2 prevents this condition.

Steam under pressure, as it passes the Venturi nozzle 31 will suddenly expand into the lower portion of the pipe 28 and this sudden expansion materially reduces the velocity of the steam flow.

It will be noted from the above description that it is possible to use this water feeder on any model of boiler installation and where it is present it is not necessary for the operator to use a pump, injector or other means of feeding the water to the boiler when the latter is under steam pressure. No matter how low the water pressure in the line 6 may be, if it is just sufficient to fill the tank 2, that is all that is necessary.

Having thus described my invention, what I claim is:

1. A water feeder for steam boilers comprising in combination a steam boiler; a water holding tank located at a level above the boiler; a valve vent pipe leading from the upper portion to the tank to the atmosphere; a valved connection leading from the lower portion of the tank to the lower portion of the boiler; a valved connection leading from the upper portion of the tank to the boiler and terminating in the latter about the normal water level thereof; and a valved connection extending from the tank to a water supply.

2. In a water feeder for steam boilers, the combination of a steam boiler; a water holding tank located at a level above the boiler; a normally open pipe connecting the upper portion of the tank with the normal water level of the boiler; a connection between the lower portion of the water tank and the lower por-

tion of the boiler; valves controlling said pipe and connection; means, when said valves are closed, for venting the water tank to atmosphere, said means including a device for retarding the flow of the steam therethrough; and means for admitting water under pressure to the tank.

3. A water feeder for steam boilers comprising in combination a steam boiler; a water holding tank located at a level above the boiler; a valved pipe connecting the upper portion of the tank with the normal water level of the boiler; a valve connection between the lower portion of the water tank and the lower portion of the boiler; a vent pipe for the upper portion of the tank, said vent pipe opening to atmosphere and being valved and provided with a Venturi nozzle to prevent undue surging of steam from the tank when the vent pipe is open; and means for feeding water to the water tank when the vent pipe is open and the other connections are closed.

In testimony whereof I have signed my name to this specification.

HERBERT EDWARD PAGE.

CERTIFICATE OF CORRECTION.

Patent No. 1,758,294.

Granted May 13, 1930, to

HERBERT EDWARD PAGE.

It is hereby certified that error appears in the printed specification of the above numbered patent requiring correction as follows: Page 2, line 115, claim 1, for the word "valve" read "valved"; and that the said Letters Patent should be read with this correction therein that the same may conform to the record of the case in the Patent Office.

Signed and sealed this 24th day of June, A. D. 1930.
